DISPENSING CONTAINER

John W. Petrie, New Haven, Conn.

Application May 2, 1946, Serial No. 666,546

1 Claim. (Cl. 206—41.2)

1

This invention relates to improvements in dispensing containers and more particularly to a container of this nature especially adapted to hold a quantity of articles, such as cigarettes, and having means provided in its structure to dispense the same one at a time.

One object of this invention is to provide a dispensing container adapted to receive and hold a plurality of articles and wherein manually operable means is provided to allow the lowermost article to drop from the container while retaining the remaining ones therein.

Another object is to provide in a container of the above nature means whereby it is adapted to hold lighted cigarettes and means to drop them one at a time at the option of the user.

Still another object is to provide in a container of the above nature improved means to release an article therefrom and means to retain remaining ones therein which means are simultaneously operable by manually actuating one of them.

A further object is to provide an improved article dispensing container which will be relatively inexpensive to manufacture, simple in construction, practical, and very efficient and durable in use.

With these and other objects in view, which will appear as the description proceeds, there has been illustrated in the accompanying drawings one form in which the invention may be embodied in practice.

In the drawings:

Figure 1 is a front face view of an article dispensing container embodying the features and principles of this invention;

Figure 2 is a rear face view of the same;

Figure 3 is a bottom view of the same; and

Figure 4 is an enlarged vertical sectional view taken on the line 4-4 of Figure 1.

Referring now to the drawings wherein like reference numerals designate like parts throughout the several views the reference numeral 11 denotes the front wall of the container body, 12 and 13 the side walls respectively, and 14 the back wall. The front and side walls 11, 12, and 13, respectively, are, in this instance, formed from a sheet of perforated material preferably metal, the sides 12 and 13 being folded backwardly at right angles to the front 11. The upper and lower edges of the front wall 11 are reinforced, the upper edge by a strip of material preferably metal 15 bent over and secured, as by soldering, to the respective edge, and the lower edge by a strip of material, preferably metal, 16, V-shaped in cross-section with its edges abutting and secured to, as

2

by soldering, the lower edge of the front wall 11.

The back wall 14 is, in this instance, a sheet of material, preferably metal, having its side edges bent over the adjacent rear edges of the side walls 12 and 13 and secured thereto, as by soldering. No top nor bottom is provided for the particular form of container illustrated, although such may be provided if desired, and in some instances it may be desirable to make the front and side-walls of unperforated material.

The form of container illustrated is particularly designed for the use of actors, for instance magicians, who may desire, during their act, to suddenly display a lighted cigarette, or the like, and therefore means, such as safety pins 17 and 18 are provided to attach the container to the user's clothing. The safety pins 17 and 18 are, in this instance, secured one to each side 12 and 13 respectively adjacent the upper portion thereof, as by soldering. In the form illustrated and preferred, the container is adapted to hold a column of lighted cigarettes, one above the other in slightly staggered relation, and preferably the container is no wider between the front and rear walls than one and one-half the diameter of the cigarettes to be disposed therein.

The means whereby articles, such as cigarettes, may be dispensed one at a time from the container comprises a supplemental rear wall 19 which consists of a flap of relatively stiff material, such as springable sheet metal, disposed within the container adjacent its rear wall 14, and a plate 21 of relatively stiff material, such as a sheet metal, disposed outside of the container adjacent its rear wall 14. The upper edge of the flap 19 is secured to the rear wall 14 by rivets 22 and is preferably spring-tensioned to normally lie against the inner face of the rear wall 14. The lower edge 23 of the flap 19 is curved inwardly from the rear wall 14 toward the front wall 11 a part of the underside of the next to the last article of the column of articles, or cigarettes, disposed in the container, to assist in supporting the articles and for a purpose to be hereinafter described.

The plate 21 is hinged to outer face of the lower portion of the rear wall 14 on a hinge pin 24 and has a portion 25 extending upwardly from this pin 24 in back of the wall 14. The plate 21 also extends downwardly from the hinge pin 24 to below the lower edge of the wall 14 whereat the plate 21 is bent forwardly toward the lower edge of the front wall 11 to underlie the lower open end of the container and provide a releasable article holding member 26. A member 27,

secured, as by soldering, to the plate 21 and extending therefrom forwardly through an opening 28, provided in the rear wall 14, into engagement with the flap 19 is provided whereby pressure applied upon the upper portion 25 of the plate 21 will cause the curved lower edge 23 of the flap 19 to be moved inwardly toward the container front wall 11 and simultaneously swing the article holding member 26 from in under the lower open end of the container. In this instance the member 27 is shown in the form of a coiled spring to provide a cushioning effect on articles within the container engaged by said flap 19.

The above described container is adapted for dispensing articles one at a time therefrom in an efficient manner. Assuming that a plurality of articles, such as cigarettes 30, are in the container as indicated in full lines in Figure 4, with the lowermost one resting upon the bent-in portion 26 of the plate 21, and the one next to the lowermost one being engaged is under a part thereof by the inwardly curved end 23 of the flap 19, and it is desired to dispense one therefrom, the user presses inwardly upon the member 25 of the plate 21. This action swings the holding member 26 from in under the open lower end of the container to release the article resting thereon and simultaneously, through the instrumentality of the member 27, presses inwardly the flap 19 to cause the curved lower end 23 thereof to press the next succeeding article forwardly against the front wall 11, and prevent it from dropping from the container as shown in dotted lines in Figure 4. When the lower end 23 of the flap 19 moves forwardly, it slightly raises the article engaged thereby, and those above this article, without damage thereto. This is partly due to the provision of a container which is no wider than one and one-half the diameter of the article, or cigarette whereby each succeeding upper one readily moves upwardly without binding, or cramping, and partly due to the curved end 23. By making the member 27 in the form of a coiled spring to cushion the pressure of the flap 19 on the articles 30, the danger of crushing them is obviated.

By perforating the front and side walls 11 and 12, 13 respectively, lighted cigarettes may be disposed in the container without becoming extinguished. Thus an actor, such as magician, can

reach under an article of clothing where the container is secured by the pins 17 and 18, and suddenly bring forth a lighted cigarette, or the like.

It will be understood that the novel features and principles of this invention may be embodied in other specific forms without departing from the spirit and essential attributes thereof, and it is therefore desired that the present embodiment be considered in all respects as illustrative, and not restrictive, reference being had to the claims rather than to the foregoing description to indicate the scope of the invention.

Having thus fully disclosed the invention, what is claimed as new and for which it is desired to secure Letters Patent, is:

In an article dispensing container having a rear wall and an open bottom through which articles in said container may pass, a springable metal flap member having a curved lower end in said container extending across and normally engaging the rear wall thereof and being fastened thereto at its upper end and movable inwardly to dispose its curved lower end into the path of movement of the articles through the container, a plate member hinged intermediate its ends to the rear wall of said container and extending downwardly therefrom, and having its lower end normally disposed under the open bottom end of said container, the lower ends of said members being vertically spaced apart to receive an article therebetween, and a coiled spring extended through the rear wall of said container above the hinge line of said plate and having one of its ends secured to one of said members and its other end engaging the other member to operably connect the same.
